UNITED STATES PATENT OFFICE

148,216

DESIGN FOR A DRUG BOTTLE OR SIMILAR ARTICLE

John F. Dennis, Toledo, Ohio

Application March 5, 1946, Serial No. 127,119

Term of patent 14 years

(Cl. D58—6)

To all whom it may concern:

Be it known that I, John F. Dennis, a citizen of the United States of America, residing at Toledo, Lucas County, Ohio, have invented a new, original, and ornamental Design for Drug Bottles or Similar Article of which the following is a specification, reference being had to the accompanying drawings forming part thereof.

Fig. 1 is a side elevational view of a drug bottle showing my new design;

Fig. 2 is a front elevation of the bottle of Fig. 1;

Fig. 3 is a partial section on the line III—III, Fig. 1;

Fig. 4 is a bottom plan of the bottle of Fig. 1; and

Fig. 5 is a rear elevation of the bottle of Fig. 1.

The dominant features of my design reside in the portions shown in full lines.

I claim:

The ornamental design for a drug bottle or similar article, as shown and described.

JOHN F. DENNIS.
